UNITED STATES PATENT OFFICE.

ALBERT T. BARRY, OF HOUSTON, TEXAS.

RAILWAY-BED AND MEANS FOR SECURING RAILS THEREON.

1,004,727.

Specification of Letters Patent.

Patented Oct. 3, 1911.

Application filed January 9, 1911. Serial No. 601,515.

To all whom it may concern:

Be it known that I, ALBERT T. BARRY, a citizen of the United States, residing at Houston, in the county of Harris and State 5 of Texas, have invented certain new and useful Improvements in Railway-Beds and Means for Securing Rails Thereon, of which the following is a specification.

My invention relates to new and useful 10 improvements in railway beds and means for securing rails thereon.

The object of the invention is to provide a bed of concrete or similar material pro- 15 vided with suitable anchors embedded there- in, and engaging with the rail, for securing 20 said rail firmly in place.

With the above and other objects in view 25 my invention has particular relation to cer- tain novel features of construction and ar- 30 rangement, an example of which is given in this specification and illustrated in the accompanying drawings, wherein:—

Figure 1 is a cross section of part of a rail- 35 way bed showing my improved anchor for 40 holding the rail thereon. Fig. 2 is a side 45 view thereof.

Referring now more particularly to the 50 drawings, wherein like numerals of refer- ence designate similar parts in each of the 55 figures, the numeral 3 refers to the road bed, composed of concrete, or some similar mate- 60 rial, and 4 refers to the railway rail.

The numeral 5 refers to a U shaped an- 65 chor which is designed to be secured to the 70 flanges of the rail and is embedded in the 75 concrete of the bed as shown in Fig. 1. This 80 anchor is composed of metal, preferably 85 steel, and the free ends thereof, which en- gage with the rail flanges, are enlarged and 40 carry inwardly extending shoulders or 45 calks 6 and 7 which engage over the rail 50 flanges, as shown in Fig. 1, and the anchor 55 thus depends from the rail.

The numerals 8 and 9 refer to shoulders 60 which are carried by the anchor and project 65 inwardly therefrom underneath the rail 70 flanges and serve as a support for the rail.

The rails are first placed in position and anchors are placed on the rail about four 50 feet apart. The anchors have sufficient 55 elasticity to permit them to be sprung apart enough to allow the shoulders 6 and 7 to engage over the rail flanges and the edges of said flanges then engage in the respective recesses formed by shoulders 8 and 9 and 60 shoulders 7 and 9. The concrete, in its plastic state, is then filled in beneath the rail until the anchors and the flanges of the rail are completely enveloped thereby as shown in Fig. 1, and the same is allowed to harden 65 and a solid road bed in thus formed, with the rail 4 firmly anchored therein. A layer of sand 10 is then placed on the concrete to serve as a cushion for the paving blocks 11 and the rails are secured against spreading, 65 in the usual manner, by means of tie rods 12, and a railway is thus constructed having a solid concrete bed with the rails firmly anchored therein.

What I claim is:—

1. In a device of the character described a U shaped anchor and two inwardly ex- 70 tends projections integral therewith, car- 75 ried by each end thereof between which the edges of a rail flange are designed to en- gage, the lower of which projections extend only a portion of the way under said rail.

2. In a device of the character described a U shaped anchor and two inwardly ex- 80 tends projections integral therewith, car- 85 ried by each end thereof between which the edges of a rail flange are designed to engage, the lower of which projections extend only a portion of the way under said rail and a concrete formation designed to hold said U 85 shaped member firmly in position upon the said rail.

In testimony whereof I have signed my name to this specification in the presence of two subscribing witnesses.

ALBERT T. BARRY.
